FRED I. JADEN, OF HASTINGS, NEBRASKA

MAIL BOX

Application filed January 30, 1929. Serial No. 336,164.

This invention relates to a mail box which may be used in rural communities and elsewhere to receive mail matter delivered by a postman, and also to hold mail matter to be picked up by the postman.

One of the objects of the invention is the provision of a mail box of improved, simple and durable construction.

Another object of the invention is the provision in a mail box of a repository or tray which is mounted in a novel manner to the end that the tray may be easily moved to the opened and closed positions; that the tray will remain in the closed position without the use of catches or the like; that the weight of the tray together with the weight of the mail matter contained therein will keep it in the closed position, and will also assist in moving the tray to the closed position, and keep it tightly closed; that the tray will remain in the open position when intentionally moved to such position; and that the tray will be moved from the opened position to the closed position, by merely imparting thereto a slight push.

The nature of the invention and its distinguishing features and advantages will appear when the following specification is read in connection with the accompanying drawings, in which—

Figure 1 is a perspective view of a mail box embodying the features of the invention.

Fig. 2 is an enlarged transverse sectional view taken on the line 2—2, of Fig. 1, and showing the tray in the opened position in full lines, and in the closed position in dotted lines.

Fig. 3 is a view of a portion of the tray and showing the stop for limiting the movement of the tray to the open position.

Fig. 4 is a sectional view taken on the line 4—4, of Fig. 3.

Fig. 5 is a sectional view taken on the line 5—5, of Fig. 2.

Fig. 6 is a perspective view of the stationary part of the box.

Fig. 7 is a fragmentary sectional view, the section being taken on the line 7—7, of Fig. 2.

Fig. 8 is a perspective view of the stop.

Referring now more particularly to the drawings, it will be apparent that the mail

box, generally stated, comprises a hollow part 10 adapted to be fixedly secured to a suitable support, and a repository or tray 11 for the mail matter, which is associated with the part 10 for movement into and out of the same to opened and closed positions.

The part 10 is made preferably of sheet metal, and requires but a single piece bent to provide, a top wall 12, end walls 13, a rear wall 14, and a front strip 15 adjoining the top wall 12. Each end wall 13 has a vertical front abutment flange 16. The top wall 12 has a downwardly projecting front edge portion 17 extending longitudinally thereof, to keep rain water from running into the tray. The rear wall 14 has holes 18 to accommodate fastening elements such as screws 19, for the purpose of attaching the part 10 to a suitable support, such as a post or wall. Each end wall 13 has a hole 20 in the forward lower corner thereof, for a purpose to appear.

The tray 11 is made preferably of sheet metal, and requires but a single piece bent to provide, a front wall 21, a rear wall 22, a bottom wall 23, and end walls 24. The front wall 21 projects above the end walls 24, and has the upper edge thereof downturned to add strength and rigidity thereto. The front wall 21 is secured in any suitable manner to flanges 25 respectively on the end walls 24.

It will be apparent that the part 10 is open at the bottom and also at the front. The tray 11 is of such size as to fit in the front opening of the part 10 defined by the front strip 15 and flanges 16. The tray 11 is connected with the part 10 for rocking or pivotal movement, to opened and closed positions. This is accomplished in the present instance by the employment of a rod 26, which extends longitudinally of the tray at the forward lower corner thereof. The opposite ends of the rod 26 are threaded as at 27, and respectively project through the end walls 24 of the tray, and also project through the holes 20 respectively in the end walls 13 of the part 10. Each end 27 has a nut 28 screwed thereon to hold the rod 26 in place. The tray 11 has a manipulator 29 for the purpose of moving the tray to the opened and

closed positions. It will now be apparent that the tray is so constructed and mounted as to be easily moved to the opened and closed positions; that the weight of the tray will 5 keep it closed, and the added weight of the mail matter contained therein, will assist in closing and keeping it tightly closed; that the tray in the opened position will remain in such position, until it is pushed slightly, 10 when it will continue to move of its own weight, to the closed position inside of the part 10, enclosing the mail matter contained therein. It will be apparent that the upper edge of the front wall 21 of the tray engages 15 the front strip 15 of the part 10, while the side edges of said wall 21 are engageable with said abutment flanges 16, thus limiting the movement of the tray to the closed position.

In order to limit the movement of the tray 20 to the opened position there is provided means presently to be described. The rear wall of the tray has an opening 30 therein near the top edge, and adjacent one end wall thereof. A piece of metal is stamped and 25 formed to produce a flat element 31 having a stop lug 32 extending in the plane of the element, a lug 33 extending laterally from said element, and a hole 34 at the lower end of said element. The element 31 is pivoted 30 to the rear wall 22 by a rivet or the like 35, which is carried by the wall 22 and which is received in the hole 34 of said element. The lug 33 projects into the opening 30 in the wall 22. The rivet or the like 35 serves 35 to set up sufficient friction between the element 31 and wall 22 to hold the element in different positions, and it will be apparent that the lug 33 is engageable with opposite walls of the opening 30 to limit the pivotal movement of the element in opposite directions, as 40 shown in Fig. 3. In one position of the element 31, its lug 32 will project beyond the related end wall of the tray, so as to engage the flange 16 on the adjacent end wall 13, 45 and in that way, limit the outward movement of the tray to the opened position, as shown in Fig. 7. The element 31 may be moved to the position shown in dotted lines in Fig. 3, in order to separate the tray from the part 50 10, for the purpose of effecting the attachment of the part 10, by driving screws 19 into the support for the box. The tray may then be associated with the part 10 in the manner explained, after which the element 31 may be 55 set in the position to dispose the stop 32 in the active position. It is to be understood that a fixed stop may be placed on the tray 11, in lieu of the one shown, in which case the tray may be separated from the part 10, 60 after the rod 26 has been removed, by lowering the tray through the bottom of the part 10.

In order to hold mail matter to be picked up for despatch by the postman, there is 65 provided an improved means in conjunction

with the mail box, presently to be described. A flat spring 36 of substantially L-shape has the portion 37 thereof extended through straps 38 struck from the bottom wall 23 of the tray 11. The said portion 37 of the spring has a hole 39 which receives a small round projection or teat 40 struck from the bottom wall 23. This keeps the spring from moving relatively to the bottom wall 23 of its own accord, yet allows the spring to be easily removed, if desired. The spring 36 also provides a portion 41 which cooperates with the front wall 21 of the tray 11 to hold one or more letters. It will be apparent that the spring 36 and the means for securing it are so devised that the spring can easily be removed without the aid of tools, if for any reason it should break, and should have to be replaced. It will also be observed that a spring so secured is not so liable to break off, as it has its full strength where the greatest strain would occur, and this is so due to the absence of rivets or other fastening elements which would weaken the spring.

I claim:

1. A mail box including a hollow section comprising top, back and end walls; a tray adapted to contain mail matter, a detachable pivot mounting the tray on said end walls of said hollow section for pivotal movement with respect to said hollow section, to opened and closed positions, an abutment on said hollow section, a stop lug on said tray engageable with said abutment, to limit the movement of the tray to the opened position, said tray being separable from said hollow section by detaching said pivot.

2. In a mail box, a hollow stationary section, a tray adapted to contain mail matter, a detachable pivot supported by said stationary section, which supports said tray for pivotal movement to opened and closed positions with respect to said stationary section, an abutment on said stationary section, and a pivoted stop lug frictionally held in a position to engage said abutment to limit the movement of said tray to the opened position, said lug being movable to a retracted position to enable the separation of said tray from the stationary section, when said pivot is detached.

3. A holding device comprising a flat spring, said spring being substantially L-shaped to conform to a section of a box, and means detachably securing said spring to said box section in cooperative position, said means consisting of straps on said box section which engage a portion of said spring, and a projection on said box section which enters a hole in said spring portion.

FRED I. JADEN.
